UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

METALLIC-PLATE WALL ELEMENT

Application filed September 24, 1928. Serial No. 307,976.

The invention relates to railway freight train cars and more particularly to metallic plate walls therefor, and consists in forming an integral strut-beam adjacent one side margin of a metallic plate which is capable of sustaining considerable compressive forces longitudinally of its length (as a column), and also capable of sustaining forces normal to its length (as a beam.) Such a construction eliminates the beam and/or post which is usually attached to one or more margins of a metallic plate when used as a wall.

Such a construction when used in house or roofed cars (such as box, automobile, stock, etc.,) would eliminate the use of corner post or door post, or if the strut-beam is positioned horizontally, would eliminate the use of the end plate or end sill. When used in open top cars (gondola) the corner post could be dispensed with.

A further object is to so form the integral strut-beam so as to provide means of securing the nailing strip for the lining of the car.

Another object is to provide a metallic wall of a railway car with a specific form of integral flange, which flange performs the usual function of the corner post, door post, end plate or end sill of a railway car.

In the drawings:

Fig. 1 shows a railway box car equipped with a typical application of my device.

Fig. 2 is a side elevation of Fig. 1.

Fig. 3 is a section on line 3—3 of Fig. 1.

Fig. 4 is a section on line 4—4 of Fig. 1.

Fig. 5 is a perspective view of a metallic plate with one margin formed into an integral strut-beam according to my invention.

Fig. 6 is a perspective view showing the connections to the frame members.

In Figs. 1 to 4 inclusive the construction is shown applied to a box car wherein the metallic plate 1 forming the end wall of the car is formed with an integral corner post adjacent each of its opposite vertical margins, which posts are secured to the upper side plates 2 and lower side sills 3, respectively, on each side of the car, or other oppositely disposed frame members.

The end portions of this integral post are Z shaped and each comprises a web 4, an in-

ner flange 5 and an outer flange 6 with the webs and inner flanges merging together between the opposite ends of the integral post to form a web 7, which web 7 is positioned obliquely to the original plane of the plate 1 and to the outer flange 6. The contour of the Z shaped end portions of the post is longer than the contour of the middle portion of the post (through the oblique web), therefore, when the end wall is pressed from a rectangular plate the outer flange is longer adjacent the middle portion of the plate (8) than adjacent the ends of the post (9), as shown in Fig. 5.

Such a construction provides a very strong column to resist stresses longitudinally of its length and furthermore constitutes a very efficient beam to resist stresses normal to its length. Therefore, such a formation provides a very efficient corner post construction.

In order to prevent the Z shape formation from opening up or becoming distorted under stress I attach the web portion 4 thereof to the sill 3 and plate 2 by members 10 and 11, respectively. I also prefer to attach the outer flange 6 to the sill by member 12 and to the plate by member 13 and further I attach the inner flange 5 to the sill by member 14 and to the plate by member 15. The flange adjacent the oblique web 7 is also preferably attached to a girth or other longitudinal frame member of the car by gusset 16. See Fig. 6 wherein the sill and plate are omitted to clarify the figure.

The metallic plate is preferably formed with integral reinforcing embossments or corrugations 30 to enable it to resist the shifting cargoes and resist the stresses set up by the weaving of the car in motion. Nailing strips 31 for the end lining 32 are positioned within or between the corrugations. A side nailing strip 33 is also provided with the integral corner post to which the inner side lining 34 is secured and also to which the end board 35 of the vertical siding is secured.

Fig. 5 is a perspective view of a metallic plate with one margin formed into an integral corner post according to my invention and clearly shows the web 4, the inner flange 5 and the outer flange 6 of the end portions

of the corner post and also shows the oblique web 7 of the middle portion of the corner post and the wide flange.

My construction may be used to perform the functions of a door post, sill or plates of the car and still come within the scope of the invention.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. In a railway car; the combination of oppositely disposed framing members, a metallic plate wall having an integral post formed at each opposite vertical margin with each of its ends secured to one of said framing members, the end portions of the post comprising a web, an inner flange and an outer flange, said webs and said inner flanges merging together between the ends of the post to form a web positioned obliquely to the plate and the outer flange.

2. In a railway car; the combination of oppositely disposed framing members, a metallic plate wall having an integral post formed at each opposite vertical margin with each of its ends secured to one of said framing members, the end portions of the post comprising a web, an inner flange and an outer flange, said webs and said inner flanges merging together between the ends of the post to form a web positioned obliquely to the plate and the outer flange, the outer flange being wider opposite the oblique web than opposite the web before it is merged with the inner flange.

3. In a railway car having a side sill and side plate, the combination of a metallic wall plate having an integral post extending between said sill and plate, said post comprising a web, and a flange, said web and flange merging together between the ends of the post to form a web positioned obliquely to the plate and the flange, and means for attaching said web to said sill and plate respectively.

4. In a railway car having a side sill and side plate, the combination of a metallic wall plate having an integral post extending between said sill and plate, said post comprising a web, and a flange, said web and flange merging together between the ends of the post to form a web positioned obliquely to the plate and the flange, means for attaching said web to said sill and plate respectively, and means for attaching said flange to said sill and plate respectively.

5. In a railway car having a side sill and side plate, the combination of a metallic wall plate having an integral post extending be-

tween said sill and plate, said post comprising a web, an inner flange and an outer flange, said web and inner flange merging together between the ends of the post to form a web positioned obliquely to the plate and the outer flange, and means for attaching said web to said sill and plate respectively.

6. In a railway car having a side sill and side plate, the combination of a metallic wall plate having an integral post extending between said sill and plate, said post comprising a web, an inner flange and an outer flange, said web and inner flange merging together between the ends of the post to form a web positioned obliquely to the plate and the outer flange, means for attaching said web to said sill and plate respectively, and means for attaching said inner flange to said sill and plate respectively.

7. In a railway car having a side sill and side plate, the combination of a metallic wall plate having an integral post extending between said sill and plate, said post comprising a web, an inner flange and an outer flange, said web and inner flange merging together between the ends of the post to form a web positioned obliquely to the plate and the outer flange, means for attaching said web to said sill and plate respectively, means for attaching said inner flange to said sill and plate respectively, and means for attaching said outer web to said sill and plate respectively.

8. In a railway car having a side sill and side plate, the combination of a metallic wall plate having an integral post extending between said sill and plate, said post comprising a web, an inner flange and an outer flange, said web and inner flange merging together between the ends of the post to form a web positioned obliquely to the plate and the outer flange, and means for attaching said inner flange to said sill and plate respectively.

ARTHUR E. SMALL.
